UNITED STATES PATENT OFFICE.

ISIDOR NASCH, OF LONDON, ENGLAND.

MACHINE FOR SEWING BOOKS.

SPECIFICATION forming part of Letters Patent No. 558,832, dated April 21, 1896.

Application filed July 5, 1892. Serial No. 438,914. (No model.) Patented in England June 10, 1891, No. 9,806, and in Germany September 1, 1892, No. 64,201.

To all whom it may concern:

Be it known that I, ISIDOR NASCH, a subject of the Queen of Great Britain, and a resident of Whitechapel, London, E., England, have invented certain new and useful Improvements in Machines for Sewing Together the Sheets or Signatures of Books, of which the following is a true description.

This invention has been patented to me in 10 Great Britain on the 10th day of June, 1891, No. 9,806, and in Germany on the 1st day of September, 1892, No. 64,201.

By this invention I produce a machine for sewing together the sheets or signatures of books which is exceedingly simple in its construction, of very great rapidity in its action, and of small cost of manufacture. It is easy of operation and adjustment, durable, and highly efficient in service. The work effected 20 by it is solid, strong, and regular, and the machine is adapted for use in binding together the sheets or signatures of books of any size and thickness.

According to this invention I make use of 25 any convenient number of needles, mounted each in separate needle-bars. These needle-bars work independently of one another and are each attached to one end of an arm or lever, the other end of which lever is pivoted 30 upon a carrying-shaft. A reciprocating motion is imparted to the needles by means of eccentrics or cams acting against the arms or levers aforesaid and operated by hand, treadle, or power. In front of the needle- 35 plate I have two loopers, which have a lateral traverse from right to left, and vice versa, and which each take a thread from the eye of one needle to the hook of another. In the drawings accompanying I have shown three 40 needles as being formed with eyes and two with hooks at their points; but the numbers of each may be varied to suit requirements. After the thread is taken from the eye of one needle by the looper to the hook of another 45 needle it is held by the latter till another thread is brought to it, when the two loops are interlocked and the stitch is formed; and in order that this invention may be fully understood and readily carried into effect I 50 will proceed to describe same, with reference to the accompanying drawings, in which simi-

lar letters and numerals of reference indicate like parts in all the figures.

Figure 1 shows in plan my improvements as applied to a machine employing three threads, 55 though it must be understood that any number of threads desired may be employed with a necessary alteration in the number of the needles in accordance therewith. Fig. 2 is an end elevation. Fig. 3 is a back or rear 60 elevation, and Fig. 4 is an inverted plan, of the machine. Fig. 5 is an enlarged detail view illustrating the guides in which the table travels. Fig. 5^a is a side elevation of the part shown in Fig. 5. Fig. 6 is a detail view in 65 side elevation of the central lever *w*². Fig. 7 is a detail of a portion of the plate *z*³. Fig. 8 is a diagrammatic view showing the needles and loopers in the position they assume at the beginning of the operation. Fig. 9 is a 70 similar view showing two of the needles and the loopers in the position assumed in the act of sewing the first signature. Fig. 10 is a similar view showing the needles retracted and the hooks advanced and the loopers 75 moved to the left. Fig. 11 shows the hooks retracted and the loopers returned to normal position ready for sewing the second signature. Fig. 12 shows the second set of needles 80 advanced in the act of sewing the second signature. Fig. 13 shows the hooks advanced and the loopers advanced to carry the thread to the hooks. Fig. 14 shows the needles returned to normal position at the completion 85 of the sewing of the second signature, and Fig. 15 shows a series of signatures which have been sewed according to the present invention.

a are the needles; *b*, the needle-bars in which the needles are mounted.

c are the arms or levers attached at one end to the needle-bars *b* and having the other end working loosely upon the carrying-shaft *d*.

e are the cams which, acting against the levers or arms *c*, impart motion in one direction thereto.

f is the driving-shaft and upon which the cams *e* are mounted. Springs *g* may conveniently, as shown, be fitted for causing the return motion, or other cams may be arranged 100 for this purpose, if desired.

The driving-shaft *f* may be operated in any

convenient manner. In the drawings here-
with it is shown as receiving its rotary motion
from the driving-wheel h through intermediate shafts i k and bevel-gears l m . This
5 motion will be seen more particularly upon
reference to Fig. 4 of the drawings. The
driving-wheel h is carried upon one end of
the shaft i , the other end of which shaft is
provided with the bevel-wheel l , the teeth of
10 which latter take into the teeth of a corre-
sponding bevel-wheel fitted upon the counter-
shaft k . At the end of the counter-shaft k
is fitted another bevel-wheel m , working in
the bevel-wheel, as shown, carried upon the
15 driving-shaft f . The loopers n are carried
by rods or bars o , sliding in bearings p . The
outer ends of these rods or bars o are con-
nected by cross-levers q to shafts r , which
have a lateral motion communicated to them
20 by means of levers and rods r' r'' , operated
from the shaft k in the following manner:

Particularly referring to Figs. 2 and 4, it
will be observed there are cams r^3 fitted upon
the shaft k . In revolving, these cams come
25 in contact with the studs r^4 upon the levers
 r^5 . These levers r^5 are pivoted at one end on
the shaft r^6 , carried in the standard r^7 , and
are each attached at other end to a pitman r^2
and communicate motion to such pitmen upon
30 the impact of the cams r^3 . The levers or arms
 r' are also and at same time actuated as the
pitmen r^2 are connected to them. These levers
 r' are pivoted at r^x and have their other ends
35 attached to the shafts r and give motion to
these latter in their turn. Through them the
looper-carrying bars o are actuated, being
connected to same by the cross-levers q afore-
said. Springs r^8 are shown as being provided
40 for the return motion of the levers and looper-
carrying bars.

Attached to the rod or bar o is a collar s ,
having a tailpiece s' , which is depressed at
each revolution of the driving-shaft by means
45 of the lever t , which is pivoted at t' and is
acted upon by a cam u , fitted upon the driv-
ing-shaft f . This causes the looper n to be
depressed slightly as it is placing the thread
upon the hook of the needle, so as to carry
50 said thread well within the jaws of the hook.
A spring s^2 (shown particularly in Fig. 3)
acting upon the aforesaid tailpiece s' of the
collar s causes the looper to resume its orig-
inal position. To more easily disengage it-
self of the loop or stitch, the hook-needle is
55 caused to partly revolve. This is accom-
plished by forming teeth at the end of the
needle-bar b , which take into a rack v , which
has a reciprocating motion given to it through
the lever v' , spring v^2 , and cam v^3 . (See Figs.
60 3 and 4.) The cam v^3 in revolving abuts
against the stud v^4 on lever v' and carries
same forward, and this lever being attached
at its upper end to the rack v causes same to
advance. The spring v^2 draws it back when
65 the cam becomes free of the stud. To take
up the slack of the thread, I provide thread-

controllers consisting of the arms w , pivoted
at w' . Cams w^3 , fitted upon the driving-shaft
 f , are revolved by the latter and take against
the pivoted arms w^2 and cause them to rise 70
and lift the arms w at the proper times—i. e.,
at each revolution of the driving-shaft.

x is the bed or stitch-board of the machine,
which is lowered automatically at each revo-
lution of the main shaft by means of a screw-
75 column x' , around which engages a threaded
collar 5 , attached to the stitch-board. The
column is caused to revolve by providing it
with a toothed portion x^4 , (see dotted lines,
Fig. 1,) which is engaged by a pawl x^3 , mounted
80 on an arm x^10 , which is journaled on the
column x' and vibrated by suitable connections
from the cam x^8 on shaft k , and y the feed-
ing-table sliding between guides y^2 . Upon
85 this table y the sheet or signature is placed
and is carried by it to the stitch-plate y' .

z are spools from whence the thread is
taken through the tensions z' and through the
aperture z^2 in guard or face plate z^3 , (this lat-
ter is provided with slots, through which the
90 thread-controlling arms are free to work,) then
through the eye z^4 , thence it is taken to the
thread-controlling arm w , and then down-
ward, passing through the eye z^5 , and on
through the eye of the needle. 95

In the operation of the machine the signa-
ture to be sewed is brought into the position
shown by dotted lines A in front of the nee-
dles, as in Fig. 8. On the further movement
of the machine the needles 1 and 3 advance 100
and penetrate the signature, and simultane-
ously the looper 6 is thrown to the right, so
that the parts assume the position shown in
Fig. 9. The needles 1 and 3 are then retracted;
but before they do so the loopers 6 and 7 en-
105 gage the threads and move to the left and
carry the threads into the path of the hooks,
which are advanced to take the threads, as
shown in Fig. 10. The loopers then release
the threads and return to normal position,
110 and the hooks recede and carry the threads
into the position shown in Fig. 11, thus com-
pleting the sewing of the signature, which is
here shown in full lines. The second signa-
ture is then fed forward into position, as 115
shown in dotted lines, Fig. 12, whereupon it
is penetrated by needles 3 and 5, the loopers
moving into position to engage the threads,
and upon the advance of the hooks the loopers
move to the right and draw the threads 120
into position to be engaged by the hooks,
which then draw the threads through the sig-
nature, and as the previous loop has up to
this time remained upon the neck of the
hook the second loop is drawn through the 125
first. The third signature then comes into
position and is sewed by needles 1 and 3 in
the manner first described, and so the opera-
tion goes on until the proper number of sig-
natures has been sewed, as shown, for ex- 130
ample, in Fig. 15. It will thus be seen that
succeeding signatures are sewed in different

places, and thus the thickness of the back of the book is much reduced, compared with those stitched by other machines sewing them all in the same place. The book also opens 5 flatter and with a much better spring than any sewed by machines heretofore in use, and the sewing is much tighter, equaling in every respect the best hand-sewing, while excelling it in strength. The signatures require no 10 cutting at the edge, and should a stitch be cut or broken it will not loosen a sheet.

Having now fully described my invention, I declare that what I claim, and desire to have secured to me by Letters Patent of the United 15 States, is—

1. In machines for sewing together the sheets or signatures of books the combination of hooks or loopers *n*, sliding rods or bars *o*, cross-levers *q*, shafts *r*, and actuating-levers, 20 rods, cams, and springs described, with complementary stitch-forming mechanism; sub-

stantially as hereinbefore described and shown.

2. In combination with the needles with means for alternately reciprocating them in 25 sets, the hooks with means for reciprocating them once for each reciprocation of the needles, the loopers with means for reciprocating them across the face of the needles to transfer the thread from each set of needles 30 to the hooks, means for rotating the loopers to insure their leaving the thread upon the hooks, and means for rotating the hooks to release the threads, substantially as described.

In witness whereof I have hereunto signed 35 my name in the presence of two subscribing witnesses.

ISIDOR NASCH.
